WEATHER STRIP FOR JALOUSIE WINDOWS

Samuel Greene, Newark, N. J.

Application March 21, 1955, Serial No. 495,427

8 Claims. (Cl. 189—62)

This invention relates to new and useful improvements in a weather strip for jalousie windows or that type of windows generally embodying a plurality of overlapping horizontally disposed glass panels swingable between vertical side stiles or jambs of the window frame.

In such type of windows, a clearance or space must necessarily be provided between each vertical side stile and the ends of the adjacent swingable clips supporting the glass panels in order to provide sufficient freedom of swinging motion for the glass panels and to facilitate the opening and closing of the window. Heretofore it has been found extremely difficult to successfully exclude rain, wind and foreign matter from blowing through such clearance or space.

Weatherstripping using hinges to move the weather stripping to open position and using resilient means such as springs to retract the stripping to normally closed position have been attempted but such devices are ineffectual for the intended purpose, are costly and are liable to get out of order.

It is therefore a prime purpose of the present invention to provide a weather strip for a jalousie window which is so constructed that it will effectively seal the space between the stile and the adjacent swingable panel supporting clips and which is supported in a novel manner upon the extruded frame of the window so that it will be effectively, positively and automatically moved to open and closed positions.

Another object of the invention is to provide a weather strip for a jalousie type window which is characterized by fewness of parts and which has no moving parts to get out of order.

A further object of the invention is to provide a weather strip for a jalousie window which needs no extraneous pivoting means such as hinges to facilitate movement to open position, and needs no extraneous resilient means such as springs to move it to closed position.

It is further proposed to produce a weather strip for a jalousie window which is simple and rugged in construction and which can be manufactured and sold at a reasonable cost.

Other objects and advantages of the weather strip will be apparent from the description thereof to follow taken in connection with the accompanying drawings in which—

Figure 1 is a substantially central vertical sectional view of a jalousie window embodying the invention, the window being shown in closed position.

Figure 2 is a horizontal sectional view taken on the plane of the line 2—2 of Figure 1.

Figure 3 is a fragmentary sectional view showing the edge of the weatherstrip positioned in the path of movement of the closing tongue when the window is in open position.

Figure 4 is a fragmentary sectional view similar to Figure 3 showing a step in the closing movement of the window.

2

Figure 5 is a fragmentary front face view of the window in closed position.

Figure 6 is a perspective view of the weatherstrip.

Referring to the drawings in detail, the numeral 1 designates a rigid and preferably extruded window frame as a whole, preferably formed of aluminum, embodying side stiles 2, a bottom rail or sill 3, and a top rail or header 4. The stiles have integrally formed outwardly projecting extensions 5 that extend for the full height of the stiles and which provide flat surfaces for end mounting clips 6 that swingably support glass panels 7.

Each clip 6 is formed with an elongated channel-shaped body having a base wall 8 with a perforated laterally extending lug 9 at one end, a straight outer side wall 10 and a tapered inner side wall 11 thereby forming a tapered channel to receive the glass panel 7. The glass panel is clamped therein by a wedge-shaped member 12.

The mounting clips 6 are pivotally supported upon the flat surfaces of the extensions 5 by pivot pins 13 extending through the base walls 8 and through said extensions. The clips and their supported panels 7 are shifted simultaneously by a common operating bar 14 pivotally connected to the lugs 9 of the clips. The bar 14 is operatively connected to a link 15 which is pivotally connected to a geared lever 16 meshing with gearing in a gear box 17 actuated by a crank 18. Spaces or gaps 19 between the surfaces of the extensions 5 on the side stiles and the bodies of the clips 6 permit such shifting movement.

The top rail or header 4 is provided with a forwardly extending drip shield 20 for substantially its entire length. The drip shield is provided with a vertically arranged lip 21 that is provided with an inwardly dovetailed groove 22 for supporting a flexible weather strip 23. The weather strip may be formed of rubber or any other suitable material for sealing the upper end of the window when in a fully closed position.

The bottom sill 3 is also provided with a flexible and deformable weather strip 24 for its length for sealing the bottom end of the window.

In accordance with the present invention, the extreme outer end of each of the extensions 5 on each side stile 2 is enlarged as indicated at 25, for its entire length. The enlarged outer end, for its entire length, and in substantial vertical alignment with the several opposed mounting clips 6, when the panels 7 are in fully closed position, is provided with a semi-circular groove 27. Elongated weather proofing strips 28 overlie the spaces or gaps 19 between the surfaces of the extensions 5 and the opposed bodies of the clips 6 when the panels 7 are in fully closed position. The weather strips each comprises an elongated flat thin body with a bead 29 along one long edge, said bead being disposed eccentrically to the plane of the body thereof, the other long edge 30 of the body being curved in a direction away from the direction of the bead 29. The beaded long edges 29 of the strips are pivotally seated in the grooves 27 in the extensions 5 and rest upon the bottom sill 3.

The weather strip 28 may be formed of extruded aluminum or other suitable material and serves to effectively seal the space or gap 19 between the side stile 2 and the opposed panels 7 against the entry of rain, wind and foreign matter when the window is in a fully closed position. The body of the weather strip is sufficiently wide to span the gap and to allow its straight free long edge 30 to overlap the surfaces of the outer walls 10 of the opposed clips 6 which are in a common plane when the glass panels 7 are in fully closed position so that the weather strip is frictionally engaged by the mounting clips during the opening of the window and turned upon its pivot beaded edge 29 to open position by said clips.

In order to provide mechanical means for retracting

the weather strip during the act of closing the glass panels 7, a tongue 31 is outstruck from the outer side wall 10 of the channel body of each clip 6, the free end tip 32 of the tongue being hooked and extending slightly laterally beyond the edge of the wall 10. When the window is closed and the weather strips 28 are in sealing position, the free long edges 30 thereof are received in the spaces underneath the tongues 31 on the clips 6.

As shown in the drawings, the weather strips 28 are supported by the extensions 5 of the side stiles 2 in alignment with and are effectively engaged by all of the panel clips 6 simultaneously when the window is in fully closed position thus providing a continuous and uninterrupted seal between the stile extensions 5 and the clips 6. This seal however permits of the pivotal mounting of the clips with adequate clearance with the stile extensions thus avoiding the usual objectionable frictional contact of the clips with the stiles, which frictional contact has always tended to retard the free operation of the window.

In use, assuming that the window is closed, then the weather strips will bridge the gaps 19 between the side stiles 2 and the opposed bodies of the clips 6.

If now the window is opened from the inside in the normal way by means of the crank 18 and connected operating bar 14, the weather strips 28 will be turned upon their pivotal edges 29 by the flat faces of the outer side walls 10 of the clips 6 initially pushing against the overlapping free long edges 30 of the weather strips, and continued outward movement of the clips will cause the flat faces of the base walls 8 of the clips to slide over the free long edges 30 of the weather strips and move the strips to fully open position extending at right angles to the front face of the side stiles, the shoulders of the clips coacting with the curved outer ends of the free edges 30 of the strips permitting this continued movement. When the weather strips are in fully open position, the tip ends 32 of the tongues 31 on the clips are disposed outwardly but in alignment with the curved outer end edges of the free long edges 30 thereof so that upon retraction of the clips 6 with the panels 7 by the operating rod 14, said tip ends 32 of the tongues engage the free end edges 30 of the strips 28 and pull the strips inwardly to fully closed position. The weatherproofing of the window is thus effected in an automatic and positive manner.

While I have illustrated and described the preferred embodiment of my invention, it is to be understood that changes in details of construction might be made without departing from the principle of the invention, and I desire to be limited only by the state of the prior art and the appended claims.

What I claim is:

1. In a metal window having side stiles, elongated glass-panel-supporting clips swingably supported on each of the stiles with spaces between the stiles and clips, means for swinging said clips, glass panels carried by said clips, weather strips pivotally supported on the side stiles in said spaces, said weather strips being in overlapping engagement with the clips in closed position so that opening movement of the clips is imparted thereto, and tongues on the clips projecting laterally outwardly of the clips and extending across the overlapping long edges of the adjacent strips in closed position, said strips being arranged so that in open position the free long edges thereof are disposed in the path of movement of the tip ends of the tongues and said strips are engaged by said tongues during closing movement of the clips for moving said strips to closed position.

2. A metal window having a frame including vertical side stiles having outwardly projecting extensions with enlarged outer end portions, each of said enlarged end portions having a groove therealong, a plurality of elongated channel-shaped glass-panel supporting clips swingably supported on each of the side stiles, glass panes in said clips, means for swinging said clips, one elongated metal weather strip pivotally supported along one long edge in the groove in the enlarged outer end portions of each of said extensions, the other free long edges of the strips being in overlapping engagement with the outer surfaces of the adjacent clips in closed position so that opening movement of the clips is imparted to the strips, and outstruck tongues on the clips projecting laterally outwardly of the clips and extending across the overlapping long edges of the adjacent strips in closed position, said strips being arranged so that in open position the free long edges thereof are disposed in the path of movement of the tip ends of the tongues and the strips are engaged by said tongues during closing movement of the clips for moving said strips to closed position.

3. A metal window having a frame including vertical side stiles having outwardly projecting extensions with enlarged outer end portions, each of said enlarged end portions having a groove therealong, a plurality of elongated channel-shaped glass-pane-supporting clips swingably supported between the side stiles, glass panes in said clips, means for swinging said clips, elongated metal weather strips, each of said strips having a beaded long edge pivotally supported in the groove in the enlarged end portion of one of said extensions, the other free long edges of the strips being in overlapping engagement with the outer surfaces of the clips in closed position so that opening movement of the clips is imparted to the strips, and outstruck tongues on the clips projecting laterally outwardly of the clips and extending across the overlapping long edges of the adjacent strips in closed position, said strips being arranged so that in open position the free long edges thereof are disposed in the path of movement of the tip ends of the tongues and the strips are engaged by said tongues during closing movement of the clips for moving said strips to closed position.

4. A metal window having a frame including vertical side stiles having outwardly projecting extensions with enlarged outer end portions, each of said enlarged end portions having a groove therealong, a plurality of elongated channel-shaped glass-pane-supporting clips swingably supported between the side stiles, glass panes in said clips, means for swinging said clips, elongated metal weather strips, each of said strips having a beaded long edge pivotally supported in the groove in the enlarged end portion of one of said extensions, the other free long edges of the strips being in overlapping engagement with the outer surfaces of the clips in closed position so that opening movement of the clips is imparted to the strips, and outstruck tongues on the clips projecting laterally outwardly of the clips and extending across the overlapping long edges of the adjacent strips in closed position, said strips being arranged so that in open position the free long edges thereof are disposed in the path of movement of the tip ends of the tongues and the strips are engaged by said tongues during closing movement of the clips for moving said strips to closed position.

5. In a metal window having side stiles, elongated panel-supporting clips swingably supported on each of the stiles, interfaces being defined between the stiles and clips, means for swinging said clips, panels carried by said clips, weather strips pivotally supported on the side stiles laterally outwardly of said interfaces, said weather strips being in engagement with the clips and extending over said interfaces in closed position so that opening movement of the clips is imparted thereto, and parts on the clips projecting laterally outwardly of the clips, said strips being arranged so that in open position they are engageable by said clip parts during closing movement of the clips for moving said strips to closed position.

6. In a metal window having side stiles, elongated panel elements swingably supported on each of the stiles, interfaces being defined between the stiles and elements, means for swinging said elements, weather strips pivotally supported on the side stiles laterally outwardly of said interfaces, said weather strips being in engagement with the panel elements and extending over said interfaces in closed position so that opening movement of the panel elements is imparted thereto, and parts on the panel elements projecting laterally outwardly of said elements, said strips being arranged so that in open position they are engageable by said element parts during closing movement of the elements for moving said strips to closed position.

7. A metal window having a frame including vertical side stiles having outwardly projecting extensions with enlarged outer end portions, each of said enlarged end portions having a groove therealong, a plurality of elongated panel elements swingably supported between the side stiles, means for swinging said elements, elongated weather strips, each of said strips having a beaded long edge supported in the groove in the enlarged end portion of one of said extensions, the body of said weather strips being in engagement with and overlapping said elements in closed position, and parts on said element projecting laterally outwardly therefrom, said strips being arranged so that in open position they are engageable by said

element parts during closing movement of said elements for moving said strips to closed position.

7. In a metal window as defined in claim 4, said clips being shaped to provide for disposition of their outer faces in a common plane when the clips are in closed position, and the free long edges of said weather strips being straight to provide for snug contact of said free long edges against said outer surfaces of the clips when the clips and the weather strips are in closed position.

8. A metal window having a frame including vertical side stiles having outwardly projecting extensions with enlarged outer end portions, each of said enlarged end portions having a groove therealong, a plurality of elongated channel-shaped panel-supporting clips swingably supported between the side stiles, panels in said clips, 10 means for swinging said clips, elongated weather strips,

5 each of said strips having a beaded long edge pivotally supported in the groove in the enlarged end portion of one of said extensions, the body of said strips being in engagement with and overlapping the clips in closed position, and parts on the clips projecting laterally outwardly therefrom, said strips being arranged so that in open position they are engageable by said clip parts during closing movement of the clips for moving said strips to closed position.
